WATCHMAN'S TIME RECORDER

Austin C. Johnson and Theodore M. Wroble,
Chicago, Ill.

Application August 14, 1936, Serial No. 96,001

5 Claims. (Cl. 234—40)

The invention relates to watchman's recording mechanism and more particularly it relates to a dial movable by suitable clock mechanism and means manually operable by the watchman or operator for punching the dial to indicate the time when the means was actuated.

It is an object of the invention to provide improved means manually operable by the watchman or operator for punching a dial of the kind described in such manner as to prevent the possibility of tampering with or injuring the dial or the elements comprising the dial punching means.

Another object of the invention is to provide a recording clock of the character described in which the dial, the mechanism for operating and the mechanisms for punching the dial are respectively positioned within a casing and are accessible only by opening a door in the casing, one of said mechanisms being operable by the unlocking of the door to record the fact of opening upon the dial.

A further object of the invention is the provision of improved means for punching a dial, said means being operable by the watchman or operator exerting a pull on a cable or wire adapted to project through the wall of a building or room housing the mechanism, one end of the cable being connected with the dial punching means in such a manner that by pulling upon the cable, the punching means is actuated to indent or pierce the dial and is automatically returned to non-operative position regardless of whether or not the pull on the cable is relinquished.

Still another object of the invention is the provision of a dial punching mechanism of the kind described which is simple in operation, inexpensive to manufacture, durable and satisfactory for its intended purpose.

Many other objects and advantages of the construction herein shown and described will be obvious to those skilled in the art from the disclosure herein given.

To this end our invention consists in the novel construction and arrangement of parts herein shown and described, and more particularly pointed out in the claims.

In the drawings, wherein like reference characters indicate like or corresponding parts:

Fig. 1 is an elevational view of the interior of a casing providing a container or housing for clock mechanism, a dial sheet rotated by the clock mechanism, and a pair of members for punching the dial sheet, the casing being normally closed by a door not shown in this view;

Fig. 2 is a view of certain elements as observed along the line 2—2 of Fig. 1 with the door in closed position;

Fig. 3 is a view of one of the dial punching mechanisms including a punch bar shown in dial punching position in full lines and in maximum retracted position in dotted lines;

Fig. 4 is a view of a portion of the dial punching mechanism shown in Fig. 3, the mechanism being in the position corresponding to the dotted line or full retracted position of the punch bar;

Figs. 5 and 6 are views along the lines 5—5 and 6—6 respectively of Fig. 3; and

Fig. 7 is a view along the line 7—7 of Fig. 1.

Referring now more particularly to the drawings, the housing or casing is generally designated by the numeral 10 and the closure or door therefor by the numeral 11. The door 11 is hingedly connected to the casing 10 by pivots 12 and is locked in closed position by a latch 13 rotatable in a manner hereinafter more particularly described to unlock the door and indent a dial sheet 17 whereby the time of unlocking the door is recorded. The casing 10 is preferably fastened to the vertical face of a wall 14 by any suitable means such as screws, bolts or the like, not shown.

A partition plate 15 provides a mounting for the dial sheet 17 and for a clock mechanism mounted in a casing generally designated by the numeral 16 fastened in any suitable manner to the partition plate 15. The clock mechanism rotates the dial sheet 17 by actuating an arbor or dial shaft 19 and is neither illustrated nor described since any ordinary clock mechanism may be used.

The dial sheet 17 is preferably circular and is provided with a central aperture 18 through which the dial shaft 19 projects to provide a mounting for a cap 20. The sheet 17 has a plurality of circumferentially arranged apertures 23, in each of which a lug 24 is positioned in close fitting relation. The lugs 24 project from a collar 25 mounted on and rotatable with the dial shaft 19. The collar 25 is connected with the shaft 19 by a key 27 and is positioned in an aperture 21 in the partition plate 15 where it is yieldingly held by one end of a spring 22 in contact with the dial sheet 17. The other end of the spring 22 abuts a horizontal plate 61 positioned in the casing 16. The clock mechanism is adapted to rotate the dial shaft 19 through one complete revolution every seven days and by reason of the operative engagement of the lugs 24 with the dial sheet 17, the latter is also caused to rotate at the rate of one revolution per week. The inner

portion of the dial sheet 17 is divided by seven equally spaced radial lines into as many areas each corresponding to and designated by a different day of the week. Each of said areas is subdivided by a radial line to provide "A. M." and "P. M." segments. The outer portion of the dial sheet 17 is provided with one hundred sixty eight equally spaced radial lines to indicate the hourly movement of the dial sheet. A plate 26, fastened 10 at one end to the partition plate 15, has its free end elevated and projecting over the sheet 17 to provide a pointer. The cap 20 is held in contact with the sheet 17 by detents 28 normally operatively engaging the shaft 19 and yieldable to 15 permit removal and remounting of the cap at the end of a week or any fraction of a week if necessary. The detents 28 have inwardly projecting flanged ends 59 positioned in an annular recess 60 in the dial shaft 19. The recess 60 has a tapered upper edge permitting the ends 59 of the detents 28 to slide thereover in removing the cap 20.

The door 11 is shown in its normally closed position in Fig. 2 with the latch 13 underlying and in locking engagement with a lug 29 formed on the adjacent edge of the casing 10. The latch 13 is yieldingly held in locked position by a spring 30 and is rotated from locked to unlocked position by a key actuated shaft 31 on which the latch is fixedly mounted. The outer projecting end of the shaft 31 is angular in cross section to receive a key operable to rotate the latch 13 to unlocked position.

In order that the dial sheet 17 may indicate 35 the time when the door 11 is unlocked by actuation of the latch 13, a cam member 32 is provided on the latch 13 in operative engagement with a punch bar 33. The bar 33 has one end fixedly mounted on the partition plate 15 and its other end projecting over the pointer plate 26. The free end of the bar 33 carries a punch 34 and its intermediate portion has a corrugation 35 operatively engaged by the cam member 32 in such a manner that rotation of the latch 40 13 to disengage the lug 29 and unlock the door 11 moves the free end of the bar 33 towards the plate 26. The plate 26 is provided with an aperture 36 in register with a corresponding recess or aperture 37 in the plate 15. The described 45 movement of the bar 33 by the cam member 32 carries the punch 34 into the aperture and pierces or indents the dial sheet 17, and thereby registers the time when the door 11 is unlocked. The punch 34 is immediately released from indenting or piercing engagement with the dial sheet 17, either by opening the door or by the 50 spring 30 rotating the shaft 31 and the cam 32 back to the position shown in Fig. 2.

The casing 10, locked as described, also provides a housing for mechanism operable to indent or puncture the slowly revolving dial sheet 17 by watchmen or others in order that their presence in the locality may be recorded. The 55 mechanism is actuated by the watchman pulling upon a chain or equivalent elongated member 38 having one end operatively engaging the mechanism and the other end provided with a ring or equivalent device 39 adapted to be grasped by the watchman in order that the chain may be pulled to set the mechanism in motion. It 60 is common practice to have the ring 39 positioned in some inconspicuous place on the outside of the wall of a building or room in which the 75 device is positioned so that the watchman in

making his rounds may thereby register his presence. It frequently happens that a watchman is tempted to neglect his duty and render the recording mechanism inoperative by pulling and fastening the chain 38 taut with the dial punching mechanism in engagement with the dial sheet 17 so that the sheet is torn or mutilated or otherwise rendered ineffective by its continuous revolution in contact with the piercing or indenting portion of the mechanism. This is usually 10 done in the early part of the night, the watchman meanwhile omitting his calls and returning later to release the chain, this being followed by a report that the device is out of order.

The invention provides improved mechanism 15 adapted to operatively engage the dial sheet 17 when the chain 38 is pulled and automatically operable to immediately disengage the sheet regardless of whether or not the pull on the chain is relinquished, thereby rendering it impossible 20 for a lazy or incompetent watchman to spoil the record. The improved mechanism comprises a relatively rigid punch bar 40 having its free end terminating adjacent the free end of the bar 33 and carrying a punch 41 overlying the registering apertures 36 and 37 in the plates 26 and 15, respectively. The normal position of the bar 40 is shown in Fig. 2 with the punch 41 contiguous to but clearing the sheet 17. A frame comprising a pair of spaced apart plates 30 42, suitably fastened to the partition plate 15, provides a support for the bar 40. The bar 40 is positioned between the plates 42 and normally rests upon a spacer member 43 as shown in Fig. 2. A rod 44, rigidly connected with and extending transversely to the bar 40, has its ends respectively projecting through short slots 45 formed in the plates 42 to provide a movable pivot for the bar. The end of the bar 40 adjacent the rod 44 comprises a pair of prongs 46 40 separated by a recess 47. The ends of the prongs 46 extend transversely to the bar 40 to provide cam surfaces for engagement with a pin 48 carried by an arm 49, the arm being adapted to enter the recess when the bar is in the position 45 shown in Fig. 4.

The arm 49 is swingable about a pivot 50 connecting it with an L-shaped lever 51, the arm being bifurcated and the lever being positioned between the bifurcated portions of the arm. The 50 lever 51 is rotatably mounted on a pivot 52 connecting the plates 42 and is normally held in the position shown in Fig. 2 by a tensile spring 53. In the normal position of the punch 41 out of engagement with the sheet 17, the rod 44 is 55 at the lower end of the slots 45 with the intermediate portion of the bar 40 resting upon the spacer member 43 with its bifurcated ends or prongs 46 bearing against the pin 48 and with 60 the arm 49 positioned in the recess 47, all as shown in Fig. 2.

The chain 38 extends through a conduit 54 provided in one wall of the casing 10, the outer edge of the conduit being uniformly tapered to 65 permit the exterior portion of the chain to extend at any angle to the conduit and be freely movable therein. The chain 38 is fastened to the lever 51 in such a manner that initial pull on the chain will rotate the lever about the pivot 70 52 against the resistance of the spring 53, from the position shown in Fig. 2 to that shown in Fig. 4 and further pull will result in the lever being moved to the position shown in Fig. 3. The initial rotation of the lever 51 about the 75

5 pivot 52 causes the arm 49 to move with it in a manner to pull the pin 48 over the slightly curved projections of the prongs 46 to the position shown in Fig. 4, the camming action of the pin 48 rotating the bar 40 away from the spacer 43, and as a result, the end of the bar carrying the punch 41 is moved away from the sheet 17 to the position shown in dotted lines in Fig. 3 and in full lines in Fig. 4. The described movement 10 of the bar 40 is resisted by a tensile spring 55, having one end fastened to a bar 56 and its other end connected with the bar 40 at a point intermediate the rod 44 and the normal contacting point of the bar with the spacer member 43. 15 Further rotation of the lever 51 resulting from continued pull on the chain 38 carries the arm 49 to the position shown in Fig. 3 wherein the pin 48 has been caused to ride over and off of the curved portions of the prongs 46 and no longer holds the bar 40 against the pull exerted 20 thereon by the spring 55. Upon the instant of release of the bar 40 from operative engagement with the pin 48, the spring 55 snaps the bar 40 back to the position of Fig. 2 wherein it rests upon the spacer 43, and as shown in the full line position of Fig. 3, the momentum of the bar 40 and the punch 41 moves the punch past its normal position to momentarily pierce the sheet 17 and also moves the rod 44 to the upper end of 30 the slots 45. The movement of the punch 41 past its normal position and the positioning of the rod 44 in the upper end of the slots 45 occurs instantaneously and the bar 40 immediately thereafter takes its normal position shown in 35 Fig. 2 wherein the punch 41 is released from engagement with the sheet 17 and the rod 44 is in the lower ends of the slots 45. The spring 55 is so constructed that it exerts a constant slight pull on the bar 40 when the latter is static and in the position shown in Fig. 2. Obviously, 40 the bar 40 will return to its normal position wherein the punch 41 disengages the sheet 17, regardless of whether the arm 49 and lever 51 are held in the position shown in Fig. 3 by reason 45 of a continuous pull on the chain 38 or whether the pull on the chain is relinquished, and there is, therefore, no possibility of the punch 41 being held in contact with the sheet.

Further operation of the device requires that 50 the arm 49 and the lever 51 be returned to their respective normal positions shown in Fig. 2 and this is accomplished by the pull of the spring 53 upon the lever as soon as the watchman has relinquished his pull upon the chain 38. The return movement of the lever 51 is limited by a stop member 58 positioned in the path of the lever. The arm 49 is returned to operative position by the actuation of the lever 51 by the spring 53, the pin 48 being meanwhile moved along and in 55 contact with the adjacent faces of the prongs 46. A spring 57, mounted on the pivot 52 operatively engages the arm 49 in such a manner as to tend to rotate the arm in clockwise direction as observed in Figs. 3 and 4. The spring 57 holds the 60 pin 48 in contact with the prongs 46 and causes the pin to ride over the curved portions of the prongs to the position shown in Fig. 2 without movement of the bar 40. The spring 57 is sufficiently strong to actuate the arm 49 as described 65 and its resilience is such that it offers only slight resistance to actuation of the arm in the opposite direction to release the pin 48 from operative engagement with the prongs 46 of the bar 40.

Thus it will be seen that we have provided 70 improved mechanism of the kind described which

is inoperable except by exerting a pull upon a tensile member such, for example, as a chain or cord and which, by reason of the pull exerted thereon, automatically records its actuation and returns to its normal inoperative position regardless of whether the pull on the cord is continued or relinquished. We have also provided locking means for a housing containing the recording mechanism actuated as described, and in addition have provided improved means for recording the time when the housing is unlocked. 10

Having thus described our invention, it is obvious that various immaterial modifications may be made in the same without departing from the spirit and scope of our invention; hence we do not wish to be understood as limiting ourselves to the exact form, construction, arrangement and combination of parts herein shown and described or uses mentioned. 15

What we claim as new and desire to secure by Letters Patent is:

1. In a device of the kind described, a frame, a sheet movable relative to the frame, a bar, means providing a movable pivot connecting the bar with the frame, a punch mounted on the bar normally out of engagement with the sheet and movable beyond its normal position towards the sheet, a stop member mounted on the frame adjacent the movable pivot and providing a fulcrum for the bar as the pivot is moved, mechanism operable to rotate the bar about said movable pivot to move the punch away from the sheet and the bar away from said stop member and then to operatively disengage the bar, means for manually actuating said mechanism, and resilient means adapted to snap the disengaged bar back to normal position in contact with said stop member, the momentum resulting from said return movement of the punch and bar carrying the punch beyond its normal position into momentary 30 punching engagement with said sheet. 35

2. In a device of the kind described, a frame, a sheet movable relative to the frame, a bar, means providing a movable pivot connecting the bar with the frame, a punch mounted on the bar normally out of engagement with the sheet and movable beyond its normal position towards the sheet, a stop member mounted on the frame adjacent the movable pivot and providing a fulcrum for the bar as the pivot is moved, mechanism operable to rotate the bar about said movable pivot to move the punch away from the sheet and the bar away from said stop member and then to operatively disengage the bar, means for manually actuating said mechanism, and resilient means adapted to snap the disengaged bar back to normal position in contact with said stop member, the momentum resulting from said return movement of the punch and bar carrying the punch beyond its normal position into momentary 60 punching engagement with said sheet, and a tensile spring and a resilient member co-operating to operatively reengage said mechanism and bar following return of the punch to its normal position. 65

3. In a device of the kind described, a frame, a sheet movable relative to the frame, a bar, means providing a movable pivot connecting the bar with the frame, a punch mounted on the bar normally out of engagement with the sheet and movable 70 beyond its normal position towards the sheet, a stop member mounted on the frame adjacent the movable pivot and providing a fulcrum for the bar as the pivot is moved, an arm operatively engaging the bar adapted to rotate the bar about said 75

movable pivot to move the punch away from the sheet and the bar away from said stop member and then to operatively disengage the arm and bar, a lever operatively related to said arm, a flexible member fastened to the lever and extending through a wall of the casing, said lever being operable by a pull on the flexible member to actuate the lever to move the arm to disengage the bar, and resilient means adapted to snap the disengaged bar back to normal position in contact with said stop member, the momentum resulting from said return movement of the punch and bar carrying the punch beyond its normal position into momentary punching engagement with said sheet.

4. In a device of the kind described, a frame, a sheet movable relative to the frame, a bar, means providing a movable pivot connecting the bar with the frame, a punch mounted on the bar normally out of engagement with the sheet and movable beyond its normal position towards the sheet, a stop member mounted on the frame adjacent the movable pivot and providing a fulcrum for the bar as the pivot is moved, an arm operatively engaging the bar adapted to rotate the bar about said movable pivot to move the punch away from the sheet and the bar away from said stop member and then to operatively disengage the arm and bar, a lever operatively related to said arm, a flexible member fastened to the lever and extending through a wall of the casing, said lever

being operable by a pull on the flexible member to actuate the lever to move the arm to disengage the bar, and resilient means adapted to snap the disengaged bar back to normal position in contact with said stop member, the momentum resulting from said return movement of the punch and bar carrying the punch beyond its normal position into momentary punching engagement with said sheet, a tensile spring adapted to move the lever back to the bar engaging position of said arm when the pull on said flexible member is relinquished, and a resilient member operable to reengage said arm with said bar upon said return movement of the lever.

5. In a device of the kind described, a casing, a closure secured to the casing, a dial sheet rotatable in the casing, a resilient bar having one end rigidly connected with the casing and the other end projecting over the dial sheet, a punch mounted on the bar normally out of engagement with the sheet and movable beyond its normal position towards the sheet, a latch rotatable to lock and unlock the closure, said bar providing a cam face and said latch providing a cam member operatively engaging said face, said cam member being movable to force the bar downwardly to operatively engage the punch with said dial sheet for an instant by rotation of the latch to lock or unlock said closure.

AUSTIN C. JOHNSON.
THEODORE M. WROBLE.
